UNITED STATES PATENT OFFICE.

WILLIAM M. PAUL, OF GALVESTON, TEXAS.

WATER-GAGE-GLASS COLUMN.

1,082,441.

Specification of Letters Patent. Patented Dec. 23, 1913.

Application filed March 7, 1913. Serial No. 752,748.

To all whom it may concern:

Be it known that I, WILLIAM M. PAUL, a citizen of the United States, residing at Galveston, in the county of Galveston and State of Texas, have invented new and useful Improvements in Water-Gage-Glass Columns, of which the following is a specification.

My invention relates to water gage glass columns for boilers, and has for an object to provide a duplex column of the type wherein flat plate glass is used for each column, which is constructed so that both columns are disposed at a convenient angle whereby they may be viewed from different positions. A column of this character is adapted especially for use upon locomotive boilers so as to permit both engineer and fireman to read the glass at all times.

20 A further object of the invention is to provide a duplex column which is composed of the fewest possible parts, and which is compact and durable so as to withstand the considerable jar incident with its use.

25 A still further object is the provision of a device of this character which is constructed so that there is no danger of either glass becoming blown out by excessive boiler pressure.

30 The invention consists in the features of construction, combination and arrangement of parts, hereinafter fully described and claimed, reference being had to the accompanying drawings, in which:

35 Figure 1 is a front elevation of the device; Fig. 2 is a rear elevation of the same; Fig. 3 is a longitudinal sectional view taken through the device; Fig. 4 is a transverse sectional view taken therethrough, and Fig. 40 5 is a transverse sectional view of the body of the device alone.

Referring to the drawings, it will be seen that my improved duplex column comprises a body 1 which is formed with wings 2 and 3 disposed, as shown, at right angles, but which may be disposed at any convenient angle. The body 1 is provided at its extremities with tubular portions 4 and 5 adapted to be connected to a boiler as shown, or in any other suitable well known manner. Each wing of the body is provided in its outer face with a longitudinal recess 6 of rectangular configuration for the reception of a portion of the corresponding gage glass 7, and is further provided with a longi-

tudinally extending, semi-cylindrical groove 8 in its inwardly bulged portion 9 in communication with the said recess 6. Each groove 8 extends for nearly the entire length of the corresponding recess, terminating at 60 a short distance from the ends of the recess.

The longitudinal opening 10 of each tubular portion of the body 1 is connected by means of the outwardly curved, branch passage-ways 11 with the adjacent ends of the 65 respective wing grooves 8. The concave wall 12 of each branch passage-way 11 serves to retard the motion of the water as caused by excessive steam pressure, and further serves to direct the same against the gage 70 glass 7 at right angles thereto and at a point substantially opposite the adjacent end portion 13 of the corresponding clamping member 14, so that undue strain will not come to bear upon the exposed portion thereof. 75

Each clamping member 14 is adapted to be secured against the outer face of one of the body wings by means of the clamping bolts 16, and completely covers the same, its end portions being rounded as at 17 to conform to the shape of the rounded ends of the wing. Each clamping member is cut away centrally as at 18 to provide a longitudinal view opening in communication with the elongated recess 19 provided in 80 the inner face of the said member for the reception of the outer portion of the corresponding gage glass. The inner portion of the recess 19 in each clamping member is extended laterally at 20 so as to leave an 85 outer fulcrum edge 21 upon the said member for engagement with the outer face of the body wing to which it is attached. The clamping bolts 16 extend through the flared openings 22 provided in the clamping member 90 in communication with the extended recess portions 20, inwardly with respect to the fulcrum edges 21, the inner ends of these bolts being removably threaded into the recesses 23 provided in the body wing. Nuts 100 24 are threaded upon the outer ends of the bolts 16 and are engageable with the rounded outer face 25 of the clamping member, inwardly with respect to the fulcrum edges 21 thereof, so that, when the said nuts are 105 tightened upon the said bolts, the inner engaging edges or jaws 26 of the clamping member will be clamped against the asbestos gasket 27 interposed between the same and the outer edges of the gage glass. A 110

rubber gasket 28 is interposed between the inner edges of the gage glass and the inner wall of the wing recess surrounding the corresponding water groove. It is to be understood, that the metal of which the clamping members are constructed is to be of such nature that the inner clamping edges of the clamping member may be sprung inwardly when the clamping members are tightened, and may be of brass, aluminum or the like.

From the foregoing description, taken in connection with the accompanying drawings, it will be apparent that I have provided a simply constructed and efficient gage glass column of the duplex type which is adapted to meet all the requirements of usage, which will retain its respective gage glasses indefinitely and which may be used conveniently in connection with any type of boiler.

What I claim is:

1. In a device of the class described, a body having lateral wings, provided in their outer faces with longitudinal gage glass recesses and with longitudinal water grooves in the inner wall of said recesses, and a tubular connecting portion provided upon each end of said body having diverging passage-ways

opening into the adjacent ends of the water grooves.

2. In a device of the class described, a body having lateral wings, provided in their outer faces with longitudinal gage glass recesses and with longitudinal water grooves in the inner wall of said recesses, and a tubular connecting portion provided upon each end of said body having diverging, outwardly curved passage-ways opening into the adjacent ends of the water grooves.

3. In a device of the class described, a body having lateral wings, provided in their outer faces with longitudinal gage glass recesses and with longitudinal water grooves in the inner wall of said recesses, a tubular connecting portion provided upon each end of said body having diverging passage-ways opening into the adjacent ends of the water grooves, a flat gage glass adapted to be positioned within each wing recess, and means by which each glass may be secured in position.

In testimony whereof I affix my signature in presence of two witnesses.

WILLIAM M. PAUL.
